UNITED STATES PATENT OFFICE.

WALTER LOOMIS HAMILTON, OF HOLYOKE, MASSACHUSETTS, ASSIGNOR, BY MESNE ASSIGNMENTS, TO SCOTT PAPER COMPANY, OF PHILADELPHIA, PENNSYLVANIA, A CORPORATION OF PENNSYLVANIA.

CHECK-CONTROLLED APPARATUS.

1,138,589.

Specification of Letters Patent.

Patented May 4, 1915.

Original application filed August 15, 1911, Serial No. 644,136. Divided and this application filed October 27, 1911. Serial No. 657,074.

To all whom it may concern:

Be it known that I, WALTER LOOMIS HAMILTON, a citizen of the United States of America, residing at Holyoke, in the county of Hampden and State of Massachusetts, have invented a new and useful Check-Controlled Apparatus, (the same being a divisional part of my application, Serial No. 644,136, filed in the United States Patent Office August 15, 1911), of which the following is a specification.

My invention relates to improvements in coin-operated mechanism or apparatus which is especially adapted for automatic, motor-operated vending machines, and consists of certain peculiar guiding and receiving means for coins, and intermediate means controlled by the coins for releasing a device to which the motor is subject and through the medium of which said motor is started and stopped together with such other elements as may be necessary to render practicable and give full effect to the apparatus, all as hereinafter set forth.

The object of my invention is to produce practicable and serviceable coin-operated mechanism for controlling or releasing motor-controlling mechanism for a vending machine, such mechanism including or being provided with means to safeguard the same by preventing tampering therewith, and with means to prevent the surreptitious withdrawal of the coins inserted in the machine.

Other objects will appear in the course of the following description.

This invention is particularly well adapted for a paper-towel-vending machine, the toweling being supplied to the machine in rolls, and short lengths of such toweling, each sufficient to serve as an individual towel, being automatically delivered in exchange for coins of the proper denomination which are deposited in the machine one at a time for that purpose, and said invention is herein illustrated in connection with such machine, although it might be applied to machines designed for other purposes.

A practical form of embodiment of the

invention (as applied for towel-vending purposes), whereby I attain the objects and secure the advantages of the same, is illustrated in the accompanying drawings, and I will proceed to describe said invention with reference to said drawings, although it is to be understood that the form, construction, arrangement, etc., of the parts in various aspects are not material and may be modified without departure from the spirit of the invention.

In the drawings, in which like numerals designate like parts throughout the several views, Figure 1 is a front elevation of a paper-towel-vending machine equipped with my check-controlled apparatus, the door of the case being open or rather removed entirely so as to expose to view the interior of said case with its contents; Fig. 2, a fragmentary detail of the fulcrum of or pivotal connection for the coin lever, the pivotal member itself being in partial section; Fig. 3, a transverse vertical section through said case, taken on lines 3—3, looking in the direction of the associated arrow, in Fig. 1, and showing the members that are in the right-hand end of the case; Fig. 4, a transverse vertical section through the machine, taken on lines 4—4, looking in the direction of the associated arrow, in Fig. 1; Fig. 5, a left-hand end elevation of the feed-rollers and the cutting-rollers, showing the gears and pinions that drive the same; Fig. 6, an interior elevation of the lower half of the case and contents as viewed from the right-hand end, the case plate at that end having been removed; Fig. 7, a sectional detail on lines 7—7, looking in the direction of the associated arrow, in Fig. 8; Fig. 8, a horizontal section through the machine, taken on lines 8—8, looking down as indicated by the associated arrow, in Fig. 1, and, Fig. 9, a transverse vertical section through the switch taken on lines 9—9, looking in the direction of the associated arrow, in Fig. 7. Other arrows, besides those mentioned above, indicate the directions of moving parts.

I will describe only briefly those parts of the machine that do not enter intimately

into the present invention, commencing with the housing, but will explain very fully the apparatus, including all devices which may be said to form portions and all closely associated parts and members that may not be actual or constituent elements of such apparatus, which constitutes the subject matter of this application. For fuller details in regard to the towel-vending machine 10 illustrated in connection herewith, attention is directed to the application of which this application is a divisional part, and to another divisional application filed on even date herewith.

15 The housing above alluded to consists of a case 1 and a door 2, the latter constituting the top, front and bottom sides of the housing or for said case, and being hinged at 5 to the back of said case at the base. The 20 door 2 is capable of being securely fastened when closed by means of a padlock (not shown) which has its shackle passed through perforated lugs 6 and 10 which are respectively mounted on the case 1 and said door. In the upper part of the door near the right-hand edge is a coin slot 11, and in the bottom of said door near the back edge is a longitudinal towel-delivery slot 12.

On the inside of each end of the case 1 is 30 a U-shaped flange 13 and a U-shaped spring 14. A shaft 15, for a roll 16 of paper-toweling, is journaled in the flanges 13. Two hubs 17 are mounted, one fast and the other loose, on the shaft 15, between the springs 35 14, and the roll 16, which has a pasteboard core 18, is in turn mounted on inwardly-directed parts 19 of said hubs. The springs 14 accommodate the supply-holding device to rolls of different lengths, serve to locate the 40 roll in the same relative position in the case, and afford the necessary tension for the same.

The toweling passes from the top and back of the roll 16, downward between two horizontal feed-rollers 20 arranged one in 45 front of the other, between horizontal cutting-rollers 21 and 22 arranged below said feed-rollers and with said cutting-roller 21 in front of said cutting-roller 22, to and through a vertical guide 23 which is supported by a horizontal floor 24 in the case 1. The floor 24 is the real floor of the case, although raised some little distance above the bottom of the door 2, it being assumed wherever said door is mentioned that the 55 same is closed unless otherwise stated. The guide 23 and the above-mentioned rollers are long enough to accommodate and handle the widest strip of toweling which the machine is capable of dispensing. The guide 60 has a flaring mouth at its upper end which opens beneath the cutting-rollers 21 and 22, and said guide opens at the bottom into the slot 12 in the door 2, which slot is of the same size substantially as is the bottom of the

guide. At 25 is represented a strip of toweling from the roll 16. 65

The floor 24 has a coin slot 26 therein, which is under and parallel with the slot 11. Below the floor 24 in front of the guide 23 is a money box 27 open at the top and 70 slidingly supported by end lugs 28-28 on ledges 29-29 on the inside of the ends of the case 1. When the door 2 is open the box 27 can be drawn forward so as to afford 75 access to the contents thereof, or can be removed altogether, but when said door is closed with said box in place the only access to be had thereto is by way of the slot 26 in the floor 24 above. The slot 26 is situated in the floor 24 adjacent to the front 80 side of the box 27. Said front side of the box is interiorly concave, and is provided with a coin-guide flange 30 which extends to the left and downward from the right-hand end of the box. The object of the 85 guide flange 30 is to receive and direct coins as they drop through the slot 26, into the interior of the box 27, or to cause them to roll away from the vicinity of said slot, otherwise the coins would be liable to pile 90 up beneath the slot and thus clog the entrance to said box. By this construction, a coin in falling or rolling through the slot 26 slides down the front of the box in an inclined position, one side of the coin resting 95 against the concave surface of said box front, alights edgewise on the flange 30, and at once rolls down said flange and said concave surface until the end of the flange is reached, when the coin drops off on to the 100 floor of the box, although it may still continue to roll, but if so its general direction is toward the left-hand back corner of the box or in any event away from the vicinity 105 of the entrance slot.

As connecting mediums between the slot 11, where the coin is introduced into the case, to the slot 26, where the coin escapes into the coin box 27 after doing its work, there are provided an approximately vertical chute 31, a lever 32, and two guide ears 33 which are separated by a space that slightly exceeds the thickness of the coin. In addition to these parts there is also a mouth-piece 34. Two lugs 35, which extend 110 inwardly from the right-hand end of the case 1, support the chute 31, the adjacent edge of said chute being attached to said lugs. The chute 31 is of usual construction, being of the size which permits a coin 115 of the proper denomination to slide freely down the same, and said chute has at its upper end the mouth-piece 34 previously mentioned. The mouth-piece 34 is mounted on a pin 36 that projects inwardly from the 120 adjacent end of the case. The mouth-piece is so hung on the pin 36 and so positioned 125 relative to the slot 11 and to the chute 31,

of which it forms a supplementary part, that normally the upper end of said mouth-piece is in open relation to said slot while the bottom end of the front side of said mouth-piece is over the open end of said chute at the bottom. The purpose of closing the upper end of the chute 31 with the mouth-piece 34 is to prevent manipulation of the apparatus by means of a wire introduced into the chute, or a coin attached to a thread so as to enable such coin to be withdrawn after starting the machine. Owing to the fact that the mouth-piece cannot be positioned so as to leave any considerable portions of the slot 11 and the upper end of the chute open at the same time, any attempt at surreptitiously or fraudulently operating the machine must prove ineffectual. If a proper coin be passed through the slot 11 into the mouth-piece 34, however, the weight of the coin after it gets below the pivotal point 36 causes said mouth-piece to rock forward at the bottom into position to admit the coin to the chute 31 and at the same time to rock rearwardly at the top and close said slot. The coin at once slides down the chute, and as soon as the mouth-piece is relieved from the weight of said coin said mouth-piece returns to former position whereby it closes said chute and opens the slot 11. In order to insure the proper working of the mouth-piece, it is arranged at an incline, the upper end being in advance of the lower end, and it is also counterweighted at 37. A deflecting finger 38, for the coin, rises from the rear edge of the chute 31 at the top, the rear wall of the mouth-piece 34 being slotted at 39 to accommodate said finger. The coin, in sliding down within the mouth-piece, strikes the finger or deflector 38, in case said mouth-piece does not swing quickly enough to open the chute, and has a wedging effect that overcomes the inertia of the mouth-piece.

Projecting below the base of the front edge of the chute 31 is a tail-piece 40, and having its ends attached to the sides of said chute and extending downwardly therefrom is a U-shaped guide 41 for the front terminal of the lever 32. The tail-piece 40 is curved and its arc is concentric with the arc described by the adjacent terminal of the lever 32. The guide 41, between the vertical arms of which the aforesaid lever 55 terminal operates, is of a length and shape and in such position as to enable said lever to make its full stroke in both directions while under the influence of said guide. At the terminal of the lever that is within the 60 guide 41 is a coin-receiver 42, which is open at the top and at the right-hand end, the floor of said receiver being formed by the lever itself and the receiver being closed at the left-hand end. The space for the

coin in the receiver 42 is in the same vertical 65 plane and parallel with the space between the ears 33, and the passageway through the chute 31 and the slot 26 are also in the same plane and parallel with each other and with the aforesaid spaces. The ears 33 rise from 70 the floor 24 and project inwardly from the right-hand end of the case 1, and they extend a little way over the adjacent edge of the slot 26. This and the opposite end of said slot are beveled downwardly to the 75 left.

It is now clear that the coin, upon entering the chute 31 in the manner previously described, drops through said chute into the receiver 42, from which latter said coin is 80 prevented from escaping by the tail-piece 40 until the lever 32 is moved downward at its free end low enough to permit the coin to roll out of said receiver under the base of said tail-piece into the space between the 85 ears 33, which it proceeds to do owing to the inclination of said lever at this time. The lever having been swung downward by the coin is now in the position indicated by dot-and-dash lines in Fig. 1, which locates the 90 receiver 42 over and quite close to the slot 26, and in such a position that said receiver can rise without the coin. As soon as the lever carries the receiver upward again, which it next proceeds to do, the slot 26 is 95 uncovered and the coin rolls through the same into the box 27, because the center of gravity of the coin is at the left of the extreme right-hand edge of said slot.

I will next describe how the lever 32 is 100 mounted and the manner in which it operates, it having been assumed in the preceding paragraph that said lever has a vertical swing at its coin-receiving terminal, without going into the matter in detail. Situated on 105 the floor 24 somewhat remote from the left-hand end of the case 1, is a casing 43, and rising from said floor within said casing is an inverted L-shaped bracket 44. The arm at the top of the bracket 44 extends to the 110 left from the upright part of the bracket, and a trip-arm 45 is pivotally mounted, between the left-hand end of said bracket arm and a bearing 46 which extends inwardly from the adjacent side of the casing 43, on a 115 pin 47 which passes through said bracket arm, said trip-arm and said bearing. The trip-arm 45 passes out through a slot 48 in the front side of the casing 43, and the front terminal of said arm is bent downwardly 120 and then forwardly to have attached thereto the lower end of a coiled spring 49. The upper end of the spring 49 is adjustably fastened by nuts 50 to an inwardly-extending lug 51 on the adjacent end of the case 1. 125 The lever 32, which is nearly as long as the case 1, is pivotally mounted at 52, a short distance from its left-hand end, on the trip-

arm 45 outside of the casing 43, and the aforesaid end of the lever is fulcrumed beneath and against a bearing edge 53 on the underside at the inner end of a lug 54 which 5 projects inwardly from the left-hand end of the case 1, said lever having a transverse notch 55 in the top to receive said bearing edge. The lever 32 and the trip-arm 45 are arranged at right-angles to each other. The 10 lug 54 is provided with two ears 56 that extend below the ends of the bearing edge 53 to receive between them the fulcrumed end of the lever 32 and prevent the same from moving laterally out of engagement with 15 said bearing edge. That portion of the trip-arm 45 that is mounted directly on the pivot 47 is slotted longitudinally at 57, and set in such slot and mounted on said pivot is a latch 58 for a switch consisting in part 20 of a movable member or section which latter said latch is designed to hold and release. The latch 58 has a hook 59 on the bottom edge behind the pivot 47, and a stop projection 60 that extends in front of said pivot 25 and under the adjacent part of the trip-arm 45 which is cut away to accommodate such projection. A portion of the trip-arm 45 is broken away in Fig. 7 to expose the projection 60 in full. The latch 58 projects behind the hook 59, and being thus counterweighted is normally positioned with the stop projection 60 up against the trip-arm 45. The trip-arm projects rearwardly over the latch and is counterweighted at 61 for 30 the reason presently to be given. There is clearance enough between the latch and the overhanging terminal of the trip-arm to enable said latch to function properly.

A switch frame 62 is secured to the floor 40 24 within the casing 43 and under the latch 58, and such frame is provided with a movable segment 63 which is pivoted at its lower end in front to the front end of said frame, at 64, and has a tooth or hook 65 on top for 45 engagement with the latch hook 59. When closed the segment 63 bears with its upper rear end on the corresponding end of the frame 62, closing the gap between such ends, and when opened said segment is swung upward, and its hook 65 encounters the hook 59 50 and rocks the latch 58 upwardly out of the way until said hook 65 passes said hook 59, when said latch rocks down into normal position again with its hook now behind the hook 65. The segment 63 is in this manner held up by the latch until a coin drops 55 into the receiver 42, then the lever 32 is swung downward on the point of fulcrum, by said coin, and carries with it the trip-arm 45 against the resiliency of the spring 49, and said arm thus rocked on the pivot 47 actuates the latch 58, through the medium of the stop projection 60, and raises the hook 59 so that said hook becomes dis-

engaged from the hook 65 and said segment 65 is released and permitted to drop and close the gap in the switch.

The lever 32 is light, the spring 49 is properly adjusted, and said lever and the trip-arm 45 with the latch 58 are nicely balanced, to the end that the weight of a coin falling into the receiver 42 is sufficient to overcome the force of the spring and all frictional and other resistance, upset the balance, and bring about the release of the segment 63. When the lever 32 is released by the coin or relieved from the weight thereof, the spring 49 asserts itself and elevates the trip-arm 45 and with said trip-arm said lever. The force of the spring 49 becomes weaker, of course, as the trip-arm and the lever approach the ends of their upward travel, said spring having expended its energy before such ends are reached, but the combined weight of the latch and trip-arm behind the pivot 50, which has been of some assistance to the spring from the start, now furnishes enough added power, owing to the new positions which the parts have already assumed, to bring about the complete restoration to normal positions and conditions of the parts being considered. By thus making use of a spring and counterweights and arranging them in the manner explained, the operation of the lever 32 90 by the coin is enhanced, because an opportunity is afforded for the coin to start said lever on its downward course before meeting with the full resistance of the spring, such resistance subsequently being overcome by 100 the momentum of the lever due to the weight of the coin.

The segment 63 is actuated upward into engaging relation with the latch 58 by means of an eccentric 66 and a lug 67 which 105 projects to the right, from the top of said segment, over said eccentric. The latter is fast on a shaft 68 which is journaled in the upright part of the bracket 47 and in the adjacent end of the case 1 after passing 110 through the intervening side of the casing 43. In the drawings the segment 63 is represented as being held up by the latch 58. The eccentric raises the segment when the high part of the periphery of said eccentric 115 passes under the lug 67, the members being so proportioned and positioned that the eccentric encounters said lug at the time it is required that the segment be swung upwardly on the pivot 64. A bow spring 69 is 120 arranged to force the segment toward the upper back end of the frame 62 or retain it in locking engagement with the latch. The contiguous faces of the hooks 59 and 65 are so arranged that very little power is 125 required to overcome the force of the spring 69 and unlock the parts when the latch 58 is tilted upward by the trip-arm 45.

In addition to the frame 62 with its movable segment 63, the switch comprises two pairs of metal contact pieces 70 fitted within said frame and segment, one pair in each, 5 and separated from the frame and segment by segmental insulators 71, one such insulator being interposed between the frame and the pair of contact pieces therein, and the other such insulator being interposed 10 between the segment and the pair of contact pieces provided for the same. The contact pieces 70 in each pair are separated from each other by a segmental insulator 72, there being such an insulator for the frame 15 62 and another for the segment 63. The contact pieces 70 on each side of the insulators 72 are connected by a wire or jumper 73 so as to insure a continuity of circuit at the joint adjacent to the pivot 64, whether 20 the segment 63 be open or closed.

The shaft 68 marks the axial center of the switch, and fast on said shaft inside of the switch is an arm 74 of insulating material and provided at its outer end with a bifurcated brush 75 of spring metal designed to 25 contact forcibly with the contact pieces 70 and to travel around practically the entire course of their inner faces, one branch of such brush traveling around the two contact 30 pieces on one side of the insulators 72 and the other branch of such brush traveling around the two contact pieces on the other side of said insulators. The space between the branches and the brush 75 enables said 35 brush to clear the insulators 72. Inasmuch as the brush 75 is insulated, when the same is in contact with the contact pieces 70, which are themselves insulated, the dead space is bridged and a circuit formed from 40 the contact piece on one side with which said brush is in engagement to the contact piece on the other side with which said brush is in engagement, and the jumpers 73 connect electrically the two contact pieces 45 on the two sides.

When the brush 75 is in the space between the upraised end of the segment 63 and the adjacent end of the frame 62, it is out of contact with the contact pieces 70 and the 50 circuit is broken at the switch, but when said segment is released and comes down on said brush such circuit is closed and it remains closed while said brush makes one complete revolution, or until the brush rides clear of the frame contact pieces into the space left 55 by the segment when again swung upwardly by the eccentric 66.

An electric motor 76 is supported on the floor 24 adjacent to the right-hand end of the 60 case 1. This motor when energized drives the feed-rollers 20 and the cutting-rollers 21 and 22. The motor 76 is in an electric circuit made up of a wire 77 which connects said motor with a suitable source of electri-

cal energy outside of the case 1 and enters 65 said case, with a wire 78, through the right-hand end thereof, a wire 79 which connects one of the jumpers 73 with said motor, and said wire 78 which connects the other jumper 73 with said source of electrical energy, together with said jumpers, the contact pieces 70 and the brush 75.

The feed-rollers 20 are merely contacting rollers of usual construction for flexible strip-actuating purposes. The front feed-roller 20 is mounted fast on a shaft 80 that is journaled at opposite ends in suitable bearings which project inwardly from the ends of the case 1. The rear feed-roller 20 is mounted fast on a shaft 81 that is journaled 75 at the left-hand end in a bearing which projects inwardly from the corresponding end of the case 1, and at the right-hand end in a bracket 82 which projects inwardly from the back side of the case. The cutting-rollers 21 80 and 22 are respectively mounted fast on shafts 83 and 84 that are journaled in the same way as the shaft 81 is journaled. The cutting-rollers are mutilated in a similar manner by having nearly one-half of each 85 omitted throughout the entire length. By thus constructing the aforesaid rollers and properly mounting them relatively on the shafts 83 and 84, provision is made for gripping the paper strip 25 during a part of each 90 revolution of said rollers, and for leaving a clear space between them for said strip during the remainder of such revolution and while the cutting rollers are inactive. The cutting-roller 21 is equipped with a longitudinal cutter 85 that projects from the full periphery or high part of said roller. The cutting-roller 22 has a longitudinal groove 86, in the periphery of its high part, to afford clearance for the cutter 85 when the 95 cutting-rollers revolve.

The motor 76 has a shaft 87 with a pinion 88 thereon. The pinion 88 meshes with a gear 89 which is rigidly connected with a pinion 90. The gear 89 and the pinion 90 100 are loosely mounted on a stud 91 which projects inwardly from the adjacent end of the case 1. The pinion 90 meshes with a large gear 92 fast on the shaft 80. Also fast on the shaft 80 is a gear 93 that meshes with a gear 105 94 of the same size on the shaft 81. Thus the feed-rollers 20 are driven, at the proper speed and in the proper directions to actuate the strip 25 downward, from the motor.

Mounted fast on the shaft 68, between the 110 casing 43 and the adjacent end of the case 1, is a large gear 95 which is driven by a meshing pinion 96 fast on the adjacent terminal of the shaft 80, and a large segmental gear 97 which imparts but one revolution to the 115 cutting-rollers 21 and 22 while the feed-rollers 20 are making half a dozen revolutions, more or less. The segmental gear 97 drives

the cutting-roller 21 directly by means of a pinion 98 fast on the shaft 83, with which said gear meshes, and the cutting-roller 22 receives the same motion, only in the opposite direction, at the same rate of speed through the medium of a gear 99 fast on said shaft and a meshing gear 100 of the same size on the shaft 84. The same means that drives the gear 95 also drives the brush arm 74, since both said gear and arm are fast on the same shaft, 68. The actuating mechanism is so timed that the cutting-rollers are driven a little faster than the feed-rollers, so as to strain the toweling strip 25, while in the grasp of the two pairs of rollers, and thus facilitate the cutting action of the member 85 on said strip, it being then, that is, while the strip is in the grasp of the bottom as well as the top rollers, that said member 20 or cutter comes into play.

The operation of the machine elements and especially of the coin-operated mechanism will be quite well understood from the foregoing, so that only the brief description 25 which follows is necessary for a clear idea of the operation as a whole. A coin is dropped through the slot 11 into the mouth-piece 34 and quickly escapes from the latter into the chute 31 and thence into the coin-receiver 42. The lever 32 is swung downward by the coin in the receiver 42, when said coin rolls out into the space between the ears 33 and from there through the slot 26 into the box 27. When depressed the lever 32 actuates the trip-arm 45 and causes the latch 58 to release the segment 63. The latter instantly snaps into its closed position, under the influence of the spring 69, and brings the upper pair of contact pieces 35 70 down onto the brush 75. This closes the circuit and the motor 76 is started. Meanwhile the lever 32 rises with the trip-arm 45, under the influence of the spring 49 and the counterweights or counterweighted parts 40 into the former position, in readiness for the next coin, and at the same time the latch 58 is swung down to locate the hook 59 in the path of the hook 65 when the segment 63 is subsequently elevated by the eccentric 66. 45 The toweling strip 25 is always in the grasp of the feed-rollers 20, but at this time hangs freely in the space between the low parts of the cutting-rollers 21 and 22, because said cutting-rollers are disposed with their high parts outwardly, as shown. Upon the closing of the circuit and the starting of the motor, the feed-rollers are set in motion and continue to revolve until said motor stops, and while thus revolving, said rollers 50 draw off more and more of the strip 25 from the roll 16. By the time enough of the paper strip is fed down through the guide 23 and the slot 12, for a towel the length of which is calculated from the cutting line to the bot-

tom edge, said strip is severed in the following manner: As the gear 95 approaches the end of its revolution, the segmental gear 97 engages the pinion 98 and thus causes the cutting-rollers to be set in motion, and before said segmental gear leaves said pinion 70 said cutting-rollers make a revolution and while making it grip said strip and the cutter 85 is projected against and severs the same. The towel cut from the strip is fed down and released by the cutting-rollers. 75 While the strip-manipulating rollers are measuring off, as it were, and severing the towel, the brush 75 is making the circuit of the switch, and when said brush arrives at the upper rear end of the frame 62 and slips 80 off of the same into the open space left by the segment 63, which is elevated just before this time into engaging relation with the latch 58, by the eccentric 66, the circuit is opened, and the motor with all of the members driven thereby stops.

In the first view portions of the toweling roll 16 and its core 18 are broken away to show one of the hub projections 19 in full, and the switch casing 46 is in section.

What I claim as my invention, and desire to secure by Letters Patent, is—

1. The combination, in check-controlled apparatus, with a lever adapted to be actuated by a coin, and a trip-arm in operative relation to said lever and provided with a latch, of an electric motor, an electric circuit for such motor, a rotary member operatively connected with said motor, a movable member in such circuit adapted to be engaged by and released from said latch, said movable member being in the path of said rotary member and capable of being actuated by the latter into engagement with said latch, and means to close such circuit through said movable member, when the latter is released from said latch.

2. The combination, in check-controlled apparatus, with a trip-arm provided with locking and releasing means, and coin-operated means to operate said trip-arm, of an electric motor, an electric circuit for such motor, an annulus in such circuit, such annulus having a pivotally attached segment adapted to be engaged by and released from 115 said locking and releasing means, a rotary member operatively connected with said motor and arranged to actuate said segment into engagement with said locking and releasing means, and a rotary member, also in 120 said circuit, with which said segment contacts, when released from said locking and releasing means, to close said circuit.

3. The combination, in check-controlled apparatus, with a lever adapted to be actuated by a coin, and a trip-arm in operative relation to said lever, said trip-arm being provided with a latch, of an electric motor,

an electric circuit for such motor, an annulus in such circuit, such annulus having a pivotally attached segment adapted to be engaged by and released from said latch, an eccentric operatively connected with said motor and arranged to actuate said segment into engagement with said latch, and a revoluble brush also in said circuit and ar-

ranged to be contacted with by said segment, when the latter is released from said locking and releasing means, to close said circuit. 10

WALTER LOOMIS HAMILTON.
